EVERETT C. HILTON, OF ANDOVER, MASSACHUSETTS, ASSIGNOR TO TYER RUBBER COMPANY, OF BOSTON, MASSACHUSETTS, A CORPORATION OF MASSACHUSETTS.

NIPPLE FOR NURSING-BOTTLES.

1,144,980.

Specification of Letters Patent. Patented June 29, 1915.

Application filed March 15, 1915. Serial No. 14,546.

To all whom it may concern:

Be it known that I, EVERETT C. HILTON, a citizen of the United States, residing at Andover, in the county of Essex and State 5 of Massachusetts, have invented an Improvement in Nipples for Nursing-Bottles, of which the following is a specification.

This invention relates to nipples for nursing bottles, and has for its object the construction of a nipple having a self-closing orifice at the end, which will be opened more or less by deflection of the wall of the bulbous end-portion, regardless of the pressure of the contents thereof or suction, thus permitting 10 the contents of the bottle to be easily withdrawn, and will be immediately and tightly closed as soon as said deflected portion or portions resume their normal conformation.

In practice the wall of the bulbous end-portion of the nipple will be deflected by the infant when compressing it during the nursing operation, but my construction has the important advantage of the orifice opening 20 by deflection of the wall as contrasted with pressure of the contents of the nipple or suction, thus involving an entirely new principle of operation. The orifice is formed by a plurality of incisions or slits made in the 25 end of the nipple, which diverge from a common point, as for instance, there may be three incisions resulting in the formation of three V-shaped projections, the apices of which meet at a common point. Upon deflection of the wall of the bulbous end-portion 30 of the nipple from any cause these projections will be moved in an outward direction, or, at least, one or more of them will be so moved, and although such movement is 35 slight, yet it is sufficient to produce a large opening in the end of the nipple; and as soon as the deflected wall resumes its normal position, said projections likewise resume their normal positions, and the orifice becomes tightly closed.

Such a nipple insures protection against impurities entering therein, and also prevents leakage at all times, both of which are important factors.

Figure 1, is a side-elevation of a nipple for nursing-bottles embodying this invention. Fig. 2, is an enlarged end-view of the nipple. Fig. 3, is an end view illustrating

the opening of the orifice by deflection of the wall of the bulbous end-portion of the nipple. Fig. 4, is a sectional detail of the end-portion of the nipple shown in Fig. 3.

The general formation or contour of the nipple here shown for illustration is of a well known type. It comprises a cylindrical base 1, having a reinforced edge-portion 2, a contracted neck 3, and a bulbous or approximately spherical end-portion 4. At the extremity of the bulbous end-portion 4, a plurality of incisions or slits 5 are made, 55 which diverge from a common point, and which are, or may be, equally spaced apart, three such incisions or slits being here shown. These incisions result in the formation of V-shaped projections 6, three being here 60 shown. Without deflection of the wall of the nipple, said V-shaped projections co-operate to tightly close the orifice, but on deflection of said wall, said V-shaped projections are caused to project outwardly, or 65 at least one or more of them, thereby opening the orifice more or less and permitting the contents of the bottle to escape or to be easily withdrawn, but as soon as the deflected wall resumes its normal position, said 70 projections likewise resume their normal positions and the orifice becomes tightly closed. This action is due primarily to the natural resiliency of the rubber of which the nipple 75 is composed. The closure being tight prevents 80 impurities from entering the nipple, and also prevents leakage of the contents 85 of the bottle.

I claim:

A nursing-bottle nipple having a plurality 90 of incisions in its end-portion diverging from a common point, forming V-shaped projections, said projections being caused to move outward to open the orifice by deflection of the wall of the end-portion of the 95 nipple, and permitted to resume their normal position to tightly close said orifice upon the deflected portions resuming their normal position.

In testimony whereof, I have signed my 100 name to this specification, in the presence of two subscribing witnesses.

EVERETT C. HILTON.
